ASMUS HANSEN, OF BERLIN-DAHLEM, GERMANY, ASSIGNOR TO FRIED. KRUPP GERMANIAWERFT AKTIENGESELLSCHAFT, OF KIEL-GAARDEN, GERMANY.

SCAVENGING INTERNAL-COMBUSTION ENGINES.

Application filed July 19, 1924, Serial No. 727,055, and in Germany July 20, 1923.

The invention relates to two-stroke explosion or constant pressure internal combustion engines in which the scavenging is effected through scavenging ports and in which the charging mixture or the scavenging air is let in and out through controlled or non-controlled ports. In carrying out the scavenging process with engines of the character stated, it is important to have the 10 fresh charge or the scavenging air effecting the scavenging of the cylinder, penetrating into the upper portion of the latter to a sufficient extent in order to completely expel the exhaust gases out of the entire cylinder.

15 This effect has hitherto been endeavored in a dotible manner. Firstly by influencing in the desired sense, by means of a substantially vertical deviating surface arranged on the front face of the piston, the scavenging air entering through the inlet ports and escaping on the opposite side of the cylinder through the outlet ports, or, secondly, by superimposing the inlet and outlet ports at the same side of the cylinder and conveying 20 the scavenging current in a closed circle over the front face of the piston along the cylinder wall and cover onto the outlet ports.

25 In both cases mentioned the scavenging current is rectangularly deviated on a certain point, from its direction; in the first-named case on its entering section at the deviating surface, in the second case, on its escaping section, at the outlet ports. This forcible change of direction, however, interferes with the continual flow of the scavenging current which is necessary for a satisfying 30 scavenging effect, and requires an increase of pressure of the scavenging air owing to the fact that, as it is well-known, these sudden changes of direction cause considerable losses in kinetic energy in every flowing 35 process. Furthermore, the above-mentioned arrangement of a deviating surface on the piston the effect of which seems besides to be rather doubtful, suffers from an unfavorable shape of the piston. The second scavenging method, of the closed circle of the 40 scavenging air, involves, besides the drawbacks already mentioned, still the following disadvantages: As the entering and the escaping air current must be led very close to each other on the inlet and outlet point, in order to not have the whole arrangement of the ports extending too much in height, a mu-

tual influence on and an interference with, 55 one another of the two oppositely directed air currents cannot be avoided. A whirling will therefore occur between the inlet and outlet points such as to cause a portion of the entering mixture or charging air to be 60 pulled along with the exhaust gases through the outlet ports out of the cylinder. This fact involves a loss in charging mixture or air and therewith also in energy, as the energy producing this air current must be furnished by the engine itself, to say nothing of the loss in fuel in explosion engines. Besides, with the aforesaid mutual arrangement of the superimposed inlet and outlet ports the piston has to pass, on the return 70 stroke, over the breadth of two ports before it will cut off the cylinder. This arrangement thus causes a considerable loss in stroke which may only be compensated by employing controlled outlet ports. Finally in this 75 scavenging method which takes place in a closed curve, a dead core of gases, rotating in itself, is formed which permanently remains in the cylinder and can be dissipated only by special measures, for instance by 80 blowing an air current through this core.

Now the invention has for its object to have a scavenging process in engines of the character stated which does not suffer from the drawbacks mentioned. This object is 85 attained according to the invention by leading the charging mixture or the scavenging air in a closed current through downwardly inclined inlet ports situated as close together as possible in the circumferential direction 90 of the cylinder, over the piston surface which is of concave shape, by leading then this current up along the opposite cylinder wall and by splitting the current by disposing the outlet ports at both sides of the cylinder so as to cause the current to reach the 95 outlet ports in two divergent partial currents, which ports penetrate the cylinder wall and cause the scavenging current to escape in a continual flow without any forcible change of direction.

The accompanying drawing illustrates an embodiment of the subject-matter of the invention by way of example,

Fig. 1 showing a longitudinal section 105 through the cylinder constructed according to the invention, of an internal combustion engine,

Fig. 2 showing the cross section on line 2-2 of Fig. 1;

Fig. 3 a longitudinal section through the cylinder on line 3-3 of Fig. 1;

5 Fig. 4 is a detail in section,

Fig. 5 diagrammatically shows the invention employed in a multi-cylinder engine.

A denotes the working cylinder and B the piston reciprocating therein. In the cylinder wall are disposed the inlet ports a^1 which have the shape of nozzles, and the two outer ports of which converge, Fig. 2, so that the entering scavenging air will converge also and stream in a closed current over the concave front face of the piston. (In the embodiment of Fig. 4 the inlet ports are subdivided by means of a guiding face a^3 .) At approximately the same level as the inlet ports are so arranged the outlet ports a^2 that they form two groups opposite each other, about on a diameter which is vertical with respect to the direction of entrance of the air, these outlet ports penetrating the cylinder wall in the oblique direction shown in 25 Fig. 2.

In case the ports are not controlled, the upper edge of the outlet ports a^2 must be situated at a level higher by the primary exhaust space x than the upper edge of the 30 inlet ports a^1 , see Fig. 1. With controlled ports the upper edges of the inlet and outlet ports may lie at the same level.

The scavenging air, after having passed over the front face of the piston, raises in 35 a broad current along the cylinder wall, oppositely to the inlet ports, then it returns on the top, near the cylinder cover, and flows, in the first likewise in closed current, downwards along the cylinder wall opposite to the first-named wall. Owing to the 40 bilateral arrangement of the outlet ports the current bifurcates, the two partial currents then flowing on both sides to the exhaust ports and entering through these into 45 the exhaust conduit.

The described method enables a radical scavenging action throughout all portions of the cylinder. As the course of the air current is quite continual, losses in pressure, as 50 they may occur with the known arrangements, cannot take place so that the scavenging pressure can be held comparatively low. Furthermore, a rotating dead core of exhaust gases cannot arise since no closed circle is formed. As the superimposed disposition of the inlet and outlet ports is entirely 55 dispensed with, the described arrangement is, further, free from any loss in scavenging air, charging mixture and fuel, as it is in- 60 avoidable with the known arrangements. Finally, the loss in stroke which in the known arrangement mentioned in second line exists due to the superimposition of the ports, is in the present arrangement dis- 65 pensed with also.

The effect of the guiding faces a^3 is illustrated in Fig. 4. In the position shown of the piston which opened the inlet port by half its area only, the air would enter, if no guiding face a^3 were present, about in the direction of the dotted arrow. By providing said guiding face the air is caused to flow in the direction of the full line arrow so that even with partially opening the inlet port the scavenging current flows in a satisfying manner.

With multi-cylinder engines the arrangement may be chosen, as shown in Fig. 5, in a manner such as to have the outlet ports fitting into two pipes C common to all the 80 cylinders and extending along both sides thereof. In this case the air is conveniently supplied by air chambers D provided between the cylinders. This arrangement enables, besides a very small structural length 85 of the engine, to have very simple cylinder castings. Finally, a pair of cylinders may be connected to each air chamber D.

Claims:

1. In an internal combustion engine cylinder, an inlet port in said cylinder for a scavenging medium under pressure, and an outlet port in said cylinder circumferentially spaced from said inlet port, whereby the scavenging medium upon introduction into 95 said cylinder executes a spiral loop therein, the burned gases being expelled thereby through said outlet port in a direction obtuse relative to the direction of the incoming current.

2. In an internal combustion engine cylinder, a cover therefor and a piston therein, a downwardly directed inlet port in said cylinder for a scavenging medium under pressure, and an outlet port in said cylinder circumferentially spaced from said inlet port, whereby the scavenging medium upon introduction into said cylinder develops a current describing a spiral loop therein determined by the piston face, the cylinder 110 wall opposite said inlet port, the cylinder cover, and the cylinder wall above said inlet port, whereby the burned gases are expelled through said outlet port in a direction obtuse relative to the direction of the incoming current.

3. In an internal combustion engine cylinder, an inlet port in said cylinder for a scavenging medium under pressure, and outlet ports in said cylinder circumferentially spaced from said inlet port at either side thereof, whereby the scavenging medium upon introduction into said cylinder executes an upward loop therein expelling the burned gases through said outlet ports in a 120 bifurcated current straddling the path of the incoming current, the directions of the outgoing currents being obtuse relative to the direction of the incoming current.

4. In an internal combustion engine cyl- 130

- inder, a cover therefor and a piston therein, a downwardly directed inlet port in said cylinder for a scavenging medium under pressure, outlet ports in said cylinder circumferentially spaced from said inlet port at either side thereof, whereby the scavenging medium upon introduction into said cylinder is deflected from the upper face of said piston to the wall of the cylinder opposite 5 said inlet port, thence to the cylinder cover, thence to the cylinder wall above said inlet port, and thence in a bifurcated current straddling the incoming current toward the outlet ports, whereby the burned gases 10 are expelled through the latter in directions obtuse relative to the direction of the incoming current.
5. In an internal combustion engine cylinder, a downwardly directed inlet port in said cylinder for a scavenging medium under pressure, and outlet ports in said cylinder circumferentially spaced from said inlet port at either side thereof, said ports lying in substantially the same plane, the axial lines of said outlet ports being at obtuse 20 angles relative to the axial line of said inlet port, as and for the purpose described.
- The foregoing specification signed at Berlin, Germany, this first day of July, 1924.

ASMUS HANSEN.
